INVENTOR

Stephen D. Field,

Pope Edgecomb & Butler.

UNITED STATES PATENT OFFICE.

STEPHEN D. FIELD, OF NEW YORK, N. Y.

UNDERGROUND TELEGRAPH SYSTEM.

SPECIFICATION forming part of Letters Patent No. 291,317, dated January 1, 1884.

Application filed May 5, 1883. (No model.)

To all whom it may concern:

Be it known that I, STEPHEN D. FIELD, a citizen of the United States, and a resident of the city, county, and State of New York, have 5 invented certain new and useful Improvements in Underground Telegraph Systems, of which the following is a specification.

My invention relates to systems for conveying and distributing electrical conductors under ground.

The object of my invention is to prevent the destruction of the insulating material incasing the conductors, both from the action of the electrical current itself in overheating the 15 insulating material and from the action of moisture, which not only serves to destroy the insulation, but which is itself a conducting medium by which the current escapes to ground.

20 My invention consists in a mode of protecting the insulation of underground conductors, which consists in maintaining (preferably in circulation) within the conduits containing the conductors one or other of the gases which do 25 not support combustion—such, for example, as carbonic-acid gas or air from which the oxygen has been removed. This gas is to be applied in a dry state, and preferably to be maintained in circulation within the conduits.

30 This invention constitutes an improvement upon the system described in Letters Patent No. 233,492, granted to me October 19, 1880, and entitled "Improvement in Underground Telegraphs." There was therein shown and

35 described a means for causing the circulation of dry air within the conduits of an underground system for the sole purpose of absorbing the moisture.

I now propose to substitute for the dry air 40 a gas or vapor, which has, in addition to the property of absorbing moisture, the advantage of being a non-supporter of combustion.

It is well known that all electrical currents develop more or less heat in the circuit of conductors which they traverse. At points of 45 high electrical resistance the heat is often sufficiently developed to cause the burning of the insulating material. This action, while primarily due to the current, is greatly aided by 50 the oxygen of the atmosphere, which frequently continues to support the combustion

at the heated point until this insulation has been completely destroyed. With the proposed gas this difficulty is overcome.

My invention is set forth in the accompanying drawing, in which is shown a closed system of conduits, A A, which is made as nearly air-tight as possible. The conductors B may be disposed in this conduit in any convenient manner. At one end is an apparatus, C, for generating or supplying the dry carbonic-acid gas or other non-supporter of combustion. This apparatus may be of any convenient form—as, for example, a retort or pressure-tank. If desired, the carbonic-acid gas may be generated 65 as required by the burning of charcoal or in other equivalent ways. At the other end of the conduit system may be placed an exhausting apparatus, D, which may also be of any convenient form—such, for example, as that 70 shown and described in the above-mentioned Letters Patent—its office being to maintain a circulation throughout the conduit system of the gas furnished at C; or this apparatus may be dispensed with and the gas caused to travel 75 through the system by virtue of its own pressure.

I am aware that in the Letters Patent alluded to above means are shown for maintaining a circulation of the dry air; but my invention consists in the application of a new agent in the place of the dry air, and is independent of the particular means employed to maintain the same in motion.

I claim as my invention—

1. The combination, substantially as hereinbefore set forth, of the insulated electrical conductors, the sealed conduit, within which said conductors are disposed, and the dry carbonic-acid gas therein maintained.

2. The mode described of preventing the combustion of the insulating material of electrical conductors, which consists in placing them in conduits within which dry carbonic-acid gas is maintained.

In testimony whereof I have hereunto subscribed my name this 2d day of May, A. D. 1883.

STEPHEN D. FIELD.
